UNITED STATES PATENT OFFICE.

JACOB HENDRIK MANTEL, OF AMSTERDAM, NETHERLANDS.

GEAR FOR BICYCLES.

SPECIFICATION forming part of Letters Patent No. 663,816, dated December 11, 1900.

Application filed July 26, 1898. Serial No. 686,954. (No model.)

To all whom it may concern:

Be it known that I, JACOB HENDRIK MANTEL, a subject of the Queen of the Netherlands, and a resident of Amsterdam, Netherlands, have invented certain new and useful Improvements in Gears for Bicycles, of which the following is a specification.

The object of my invention is to provide a simple and effective gear for bicycles in which beveled gearing is used instead of the sprocket-chain, and the features of my invention will be described fully hereinafter and particularly pointed out in the claims.

In the accompanying drawings, Figure 1 shows the invention in a horizontal section. Fig. 2 is a side view. Fig. 3 is a transverse section at the rear wheel. Fig. 3^a represents the axle-box in section; Fig. 3^b, the axle-pin alone. Fig. 4 is a sectional view through one of the covers at the crank-shaft.

The driving-axle D, with the bevel-wheel S at the rear, is arranged in a completely-closed casing which fits with a projecting ledge l in a groove t of the bell G surrounding the toothed wheel S', said bell being formed on the rear-wheel hub F, whereby the whole driving-gear is tightly incased and kept dust-proof. This casing on the sleeve P, as shown in the figures, consists of a round flat plate P', with the bent ledge l and a cylindrical main piece P for the driving-axle D and the ball-bearing Z of the same, said main piece being provided with a bulge P² for the bevel-wheel S. The plate P has only a single small opening o, through which the bevel-wheel S gears with the bevel-wheel S', set on the hub of the rear wheel. The frame-tube, as shown in the drawings, is soldered to the cylindrical part P, and the upper tube 40 of the rear-wheel fork rests on this part, while it makes up a whole with the plate P', Figs. 1, 2, and 3.

The rear-wheel axle consists of a pin E within a hollow box e, on which the cones e' are located, one of which is set in by means of a set-nut e², the box being borne in the hub of the wheel and remaining there in case that the wheel should be taken out of the frame.

50 The pin E is provided with the thread E' for the purpose of screwing it into a bore p of the plate P' of the casing P, incasing the

gear at the rear wheel, and its other end possesses a thread on a swelling E², over which the step L is screwed on, said pin running 55 out into a square head.

In order to insert the rear wheel, it is set into the frame, and the latter is bent out until the ledge l has penetrated the groove t of the bell G. Then the pin E is inserted, and 60 it is first set through the bore in the frame end H. Then it is placed through the box e and thereafter screwed by its thread E' into the bore p of the plate P' until the swelling E² comes to lie against the extremity of the 65 box. Thus the pin connects firmly the axle with the plate p' of the casing P and with the one tine of the rear-wheel fork. Hereafter the step L is turned on the pin until the other side of the frame presses firmly 70 against the counter-screw l² of the cone e' and against the box e, whereby the axle is firmly connected with the frame at this side as well.

The bore in the part H of the frame is not provided with a thread. 75

When the rear wheel is taken out, the step L is first screwed off from the swelled part E² of the pin E, and then the latter is turned away from the plate P' by seizing it at its square E³. Thereafter the pin can be pulled 80 out from the box e when the frame is pulled asunder a little, so that the ledge l is liberated from the groove t in the bell G, and the toothed wheel S' is disengaged from its engagement with the toothed wheel S. Thus the 85 rear wheel, with the box e, will fall out from the frame. In combination with this arrangement of the rear-wheel axle the ball-bearings for the driving-axle D are also arranged in a simple manner. In the present arrangement 90 the ball-bearings for the driving-axle D are housed at the side of the rear axle behind the bevel-wheel S in the cylindrical part of the casing P and at the other end of the driving-axle in the loose cover B of the crank-axles. The driving-shaft D is provided at each extremity with conical projections s and s', which run on the balls in the ball-bearing cups z and z'. This execution simplifies considerably the arrangement at the crank-axle 100 casing. The ball-bearing cup Z is screwed into the cylindrical part of the casing P, set in with the counter-screw z, and so closes this part. Both ball-bearings of the driving-axle

lie at the outer side of the bevel-wheels S R', and this arrangement of the bevel-wheels on the driving-axle between the ball-bearings forms an efficient arrangement.

5 As will be seen from the drawings, the dust-cap K for the bevel-wheel R', which engages with the large bevel-wheel R on the crank-axle C, is simply screwed on at the side of the crank-axle to the loose cover B of the crank-
10 axle casing and to the frame of the bicycle.

Finally it should be stated that the described arrangement allows also a rectangular position of the bevel-wheel gear in deviation from the drawings.

15 I claim—

1. In combination, the axle-pin E having a swelling E², the box or sleeve e surrounding the axle-pin, and having a fixed cone at its end, the part P' to which the axle-pin is secured and adjacent to which the fixed cone is located, the cone e' adjustable on the other

end of the sleeve e and within the wheel-hub and the nut e² for locking the adjustable cone e', said cone and nut being within the frame, and the step L screwed on the swelling E² 25 outside the frame, said swelling E² serving to force the sleeve tight against the plate P', substantially as described.

2. In combination in a cycle, the crank-shaft, the rear wheel, the drive-shaft D, the 30 gearing between the crank-shaft and rear wheel respectively and the drive-shaft, the loose cover B at the crank-shaft and the ball-bearings for the said crank-shaft and drive-shaft carried by the said cover, substantially 35 as described.

In witness whereof I have hereunto set my hand in presence of two witnesses.

JACOB HENDRIK MANTEL.
